ELECTRIC BLANKET CONTROL OR THE LIKE

Donald B. Lowe, Jr., Batavia, Ill., assignor to Northern Electric Company, Chicago, Ill., a corporation of Delaware

Filed Jan. 30, 1961, Ser. No. 63,737

Term of patent 14 years

(Cl. D26—13)

五五五.1

五五五.2

FIGURE 1 is a front elevational view of an electric blanket control, or the like, showing my new design, the view being taken perpendicularly to the front face thereof;

FIGURE 2 is a side elevational view thereof;

FIGURE 3 is a top view thereof on a slightly reduced scale, the view being taken perpendicularly to the top surface thereof;

FIGURE 4 is a bottom view thereof, the view being taken perpendicularly to the bottom surface of the main body portion; and

FIGURE 5 is a rear elevational view thereof, the view being taken perpendicularly to the rear surface.

The dominant features of my design reside in the full line portions of the drawings.

I claim:

The ornamental design for an electric blanket control or the like, substantially as shown and described.
